UNITED STATES PATENT OFFICE.

CYRUS ROBINSON, OF MOUNT VERNON, NEW YORK, ASSIGNOR TO METALLURGICAL
ENGINEERING & PROCESS CORPORATION, A CORPORATION OF NEW YORK.

AGITATOR FOR ORE TREATMENT.

1,156,372.

Specification of Letters Patent. Patented Oct. 12, 1915.

Application filed August 16, 1912. Serial No. 715,515.

To all whom it may concern:

Be it known that I, CYRUS ROBINSON, a subject of the King of Great Britain, residing at Mount Vernon, in the county of 5 Westchester and State of New York, have invented certain new and useful Improvements in Agitators for Ore Treatment, of which the following is a specification, reference being had therein to the accompanying 10 drawings.

This invention relates to improvements in agitating devices, especially devices adapted and intended for agitating ore pulp or other material containing soluble ingredients and 15 a solvent adapted to act upon the said soluble ingredients.

It is well known that in many cases the principal difficulties and expenses incident to the chemical extraction of metal values 20 from ores is due to the necessity for mechanically agitating the solution and ore and to the time required for completing the process. These difficulties are especially prevalent in the treatment of slimes, or of 25 pulp containing an unduly large proportion of slimes. It is also well known that stirring a mixture of solvent solution and ore continuously does not result in more than approximate breaking up of the mixture, as 30 the solvent and the particles of ore tend to move together in the same relative positions. It is probably correct to state that a particle of ore containing metal is surrounded by a film of the solution and that this immediate 35 film or envelop of solvent becomes very quickly saturated. The further dissolving of metal however practically stops until the film of saturated solution can be removed from the particles and replaced by a new film of 40 active solution. That this condition exists is borne out by the fact that it is found in plants using the percolation process that the first treatment with a strong solution merely "loosens" the values but does not remove 45 them. Several subsequent washings with weaker solutions and fresh water are needed to remove the values, *i. e.* to break up and carry the films of strong value containing 50 solutions which have formed about the ore particles.

In my co-pending application for agitators for ore treatment, Serial No. 584,868, filed October 1, 1910, I have shown and described an agitator constructed and adapted 55 to vigorously agitate the mixture of solution

and ore to continually break up the films of saturated solution and separate them from the ore particles so that there is positive assurance that all of the ore and solution receives the same treatment during the travel 60 through the agitator. By my present invention I have provided an agitator similar in many respects to that shown and described in my said copending application.

The principal object of the invention is to 65 provide improved means for controlling and regulating the air or other agent by means of which agitation is effected.

A further object is to provide improved structural features for an agitator of this 70 class.

Still further objects will be apparent from the following specification and claims.

In the accompanying drawings which form a part of this specification I have 75 shown the construction which I now deem preferable, but it will be understood that many changes and modifications may be made within the scope of my invention.

Of the drawings, Figure 1 is a plan view. 80 Fig. 2 is a longitudinal sectional elevation taken along the line 2—2 of Fig. 1. Fig. 3 is a sectional plan view taken along the line 3—3 of Fig. 2. Fig. 4 is a cross-sectional view through one of the agitating chambers 85 taken along the line 4—4 of Fig. 1. Fig. 5 is a detailed sectional view of one of the valves.

Referring to the drawings, it will be noted that the agitator comprises a series of chambers or receptacles 1, 1, these being preferably arranged in two parallel rows. In the drawings I have shown but a small number of these receptacles but it will be understood that the exact number to be used will 90 depend upon the conditions under which the agitator is to operate. I have found, however, that in some cases the best results are obtained when fifty or more of these separate agitating chambers are provided. 95

The chambers of each row are preferably constructed by forming one long large tank, preferably of sheet metal and dividing this tank at the proper intervals by transverse partitions. As shown in the drawings, each 100 of these tanks is supported by two parallel channels beams 2, 2. Each tank has parallel vertical side walls 3, 3, vertical end walls 4, 4, and a bottom comprising a narrow flat horizontal part 5, and two inclined walls 6, 110

6. All of these parts are preferably formed of sheet metal and are suitably connected together and to the supporting beams 2, 2 by means of bolts or rivets. Preferably the 5 tops of the side walls are reinforced by means of angle bars 7, 7.

The bottom part of each tank, which is V-shaped in cross section, is divided into a series of hopper-like pyramidal compartments 10 by means of oppositely inclined walls 8, 8, and 9, 9, which are preferably formed of sheet metal and secured to the walls 6, 6 by means of suitable flanges and rivets. Extending upward from the lines at which the 15 several pairs of walls 8 and 9 join are transverse partitions 10, 10, which are secured at their edges by means of flanges and rivets to the main side walls 3, 3. At the tops of the partition walls 10, 10, and preferably 20 formed integrally with them, are transverse walls 11, 11, forming substantially horizontal ledges or shelves extending from one side of the tank to the other. At the end of each of the shelves 11 is an upstanding flange 25 or lip 12, which extends entirely across the tank. It will be seen that by the construction which I have described there are provided two separate series of closely adjacent receptacles or chambers each with vertical 30 side walls and a pyramidal hopper-like bottom. As will be hereinafter described in detail, means are provided for transferring material from each receptacle or chamber to the next, the material being initially fed 35 through a trough 13, to the receptacle at the initial end of the first series. An inclined chute or trough 14 is provided for transferring the material from the last receptacle of the first series to the first receptacle of the 40 second series. A spout 15 is provided for discharging the material from the last receptacle of the second series.

Each of the receptacles is provided with means for agitating the material contained 45 therein and for delivering it to the next receptacle in the series.

The agitating and transferring devices for all of the receptacles are similar and a description of one of them will be sufficient. 50 In each receptacle is a vertical tube or pipe 16 which extends through an aperture in the corresponding shelf 11. The tube is supported in part by the shelf and in part by a clamp 17, which extends transversely of the 55 receptacle. At the upper end of the tube 16 there is a hood 18 which closely engages the top of the pipe, preferably being threaded thereon and has an opening above the shelf 11 and directed toward the next adjacent 60 receptacle. At the bottom of each receptacle and in axial alinement with the tube 16 is an air pipe 19 which terminates in a nozzle 20 in the receptacle. The nozzle 20 is provided at 21 with an inclined or beveled valve 65 seat and a conoidal valve closure 22 is pro-

vided to rest upon this valve seat. The valve closure is preferably provided with a depending finger 23 which serves to hold it against lateral displacement and with a vertical stem 24 which extends upward 70 through the tube 16 and through a suitable aperture in the upper part of the hood 18. The valve closure 22 and the stem 24 are freely movable upward and the stem 24 serves to steady the valve closure and to hold it in upright position and also serves as a weight to tend to hold the valve closed. 75

It will be observed that the device 22 serves to close the nozzle 20 by gradually reducing the effective cross area thereof. The 80 pointed end 23 of the said device projects into the orifice of the nozzle, and the air is permitted to flow only through the annular space surrounding this pointed end. As the air pressure decreases the pointed end 23 extends farther and farther into the nozzle until finally the device 22 seats itself, thus entirely closing the orifice. It will be seen that with this construction the full air pressure is maintained at the place of discharge, 90 thus maintaining the maximum air velocity. It will be understood that if the closure or check valve were located at any place other than at the extreme end of the air pipe or nozzle the air pressure would be reduced 95 thereby and the velocity of air flowing from the end of the pipe would be reduced.

Below each of the rows of agitating receptacles is an air manifold 25, with which the air pipes 19, 19 are connected. The two 100 manifolds 25, 25 are connected together by a cross pipe 26 and air is supplied through a main pipe 27.

In operation, the ore pulp to be treated is supplied at a uniform rate through the inlet 105 trough 13. Air pressure is maintained in the manifolds 25, 25, and from them air passes up through the pipes 19, 19, and the nozzles 20, 20 to the tubes 16, 16. When the apparatus is first started it may be found 110 desirable to hold closed all of the valves except those in the first chambers which contain ore pulp, but as soon as the chambers have all become filled the valves are all left free to be opened by air pressure. The air 115 passing through the pipe 19 and the nozzle 20 acts upon the valve closure 22 and lifts it slightly. The air then rushes outward and upward around the conical closure and passes 120 upward in a diffused stream through the tube 16. This rapidly upward moving air has several functions. It thoroughly agitates the pulp mixture within the tube 16 and causes breaking up of the normally fixed 125 relationship of ore and solvent sub-masses. By mixing with the pulp it lightens the column within the tube 16 and causes its upper end to rise to a level considerably above that of the pulp in the outer part of the receptacle. And, as it emerges from the pulp at 130

the upper surface of the column it carries with it finely divided globules which are dashed against the upper parts of the hood 18 with sufficient force to completely break them up. From the walls of the hood 18 the very finely divided sub-masses of ore and solution are deflected downward and a considerable proportion of them reach the shelf 11 and from it are discharged by gravity 10 into the next agitating receptacle. In this way there is maintained a continuous flow of pulp from each receptacle to the next and there is assurance that each ore particle will come in contact with a fresh film of solvent 15 solution as it enters each new receptacle.

It is obviously desirable that the agitating action in each receptacle be the same as that in each other receptacle, and it is largely for this reason that I have provided the automatic valves for the air pipes 19. It is clear that in the absence of air pressure each valve will be held closed by its own weight and by the weight of the superposed liquid. Normally, the pressure in the air main and 20 manifolds is kept somewhat greater than that actually needed to cause the required agitating action in the tubes. This air pressure serves to lift the valve closures 22 from their seats and within certain limits the valve 25 closures serve to regulate and equalize the quantity and velocity of the air delivered to the tubes. I have found that without valves such as I have shown, there is a tendency for the action to be more rapid in some of 30 the tubes than in others, and this tendency is cumulative. If the level in any receptacle once falls below normal, the back pressure on the air is correspondingly reduced and the flow of air increases. This increased 35 flow of air causes an increase in the rate of discharge from the top of the tube thus still further reducing the level of the pulp in the receptacle. The final result is that some of the receptacles are kept practically empty 40 while others are filled to overflowing. By means of the valves which I have provided, this result is entirely prevented. The valves, on account of their weight, serve to prevent the too rapid flow of air in any one tube and 45 insure uniformity of action throughout the whole agitator. With valves such as I have shown it is possible for a reserve pressure above that actually required to be maintained in the manifolds without the discharge 50 into the tubes of too great a quantity of air or of air at too high a velocity. In addition to equalizing the action in the several tubes the valves serve to distribute the air in each tube and to cause it to flow upward 55 at a number of peripherally arranged points and along a number of relatively widely separated lines instead of in one stream at the center of the tube. The valves at the end of the pipes 19 also have the very 60 important function of serving to check the 65

downward flow of pulp when the air pressure is reduced. Obviously, without the valves the pulp would flow downward into the manifolds in the case of failure of air pressure.

70

What I claim is:—

1. In an agitator for ore treatment, the combination of a receptacle adapted to contain a mixture of solvent solution and finely divided ore, a vertical tube mounted in the receptacle and terminating at its lower end above the bottom of the receptacle, an air nozzle at the bottom of the receptacle below and closely adjacent the lower end of the tube, means for delivering air to the nozzle 80 to agitate the mixture in the tube and force it upward therethrough, means supplemental to the receptacle for receiving the mixture from the upper end of the tube, and means for entering the nozzle to cut down 85 the effective cross area thereof.

2. In an agitator for ore treatment, the combination of a receptacle adapted to contain a mixture of solvent solution and finely divided ore, a vertical tube mounted in the receptacle and terminating at its lower end above the bottom of the receptacle, an air nozzle at the bottom of the receptacle below and closely adjacent the lower end of the tube, means for delivering air to the nozzle 90 to agitate the mixture in the tube and force it upward therethrough, means supplemental to the receptacle for receiving the mixture from the upper end of the tube, and means automatically tending to enter the 100 nozzle to reduce the effective cross area thereof and finally close it as the air pressure is diminished.

3. In an agitator for ore treatment, the combination of a receptacle adapted to contain a mixture of solvent solution and finely divided ore, a vertical tube mounted in the receptacle and terminating at its lower end above the bottom of the receptacle, an air pipe connected with the receptacle at the bottom thereof below the lower end of the tube for delivering a stream of air to agitate the mixture in the tube and force it upward therethrough, means supplemental to the receptacle for receiving the mixture from the upper end of the tube, and a device adjacent the end of the air pipe for distributing the air and causing it to be delivered to the mixture for movement upward through the tube 110 along a plurality of relatively widely separated lines.

4. In an agitator for ore treatment, the combination of a receptacle adapted to contain a mixture of solvent solution and finely divided ore, a vertical tube mounted in the receptacle and terminating at its lower end above the bottom of the said receptacle, an air pipe having a terminal nozzle positioned directly below the lower end of the tube and provided with a valve seat, a valve closure 125

130

adapted to rest upon the said valve seat, a valve stem connected at its lower end to the valve closure and extending vertically upward therefrom through the tube, and a 5. guide for the upper end of the stem.

5. In an agitator for ore treatment, the combination of a receptacle adapted to contain a mixture of solvent solution and finely divided ore, a vertical tube mounted in the 10 receptacle and terminating at its lower end above the bottom of the said receptacle, a shelf having an aperture through which the upper end of the tube projects, a deflector above the upper end of the tube, an air pipe 15 having a terminal nozzle positioned directly below the lower end of the tube and provided with a valve seat, a valve closure adapted to rest upon the said valve seat, and a valve stem connected at its lower end to 20 the valve closure and extending vertically upward therefrom through the tube and through a suitable aperture in the deflector.

6. In an agitator for ore treatment, the combination of a receptacle adapted to contain a mixture of solvent solution and finely divided ore, a vertical tube mounted in the receptacle and terminating at its lower end above the bottom of the said receptacle, an air pipe having a terminal nozzle positioned 25 directly below the lower end of the tube and provided with a valve seat, a valve closure adapted to rest upon the said valve seat, a valve stem connected at its lower end to the valve closure and extending vertically up- 30 ward therefrom through the tube, a guide for the upper end of the stem, and a depend- 35 ing finger on the valve closure positioned to lie within the nozzle aperture and to engage the walls thereof to hold the valve closure 40 against lateral displacement.

7. In an agitator for ore treatment, the combination of a series of closely adjacent receptacles for containing a mixture of solvent solution and finely divided ore, there 45 being a common dividing wall between each receptacle and the next adjacent one, a series of vertical tubes, one mounted in each receptacle with its lower end separated from the bottom of the receptacle, a series of air 50 pipes each arranged to deliver air to one of the receptacles directly below the tube to agitate the mixture in the tube and force it upward therethrough, and a series of shelves each arranged to receive the mixture delivered 55 from the upper end of one of the tubes and to guide it over the common dividing wall and into the next adjacent receptacle.

8. In an agitator for ore treatment, the combination of a series of closely adjacent 60 receptacles for containing a mixture of solvent solution and finely divided ore, there being a common dividing wall between each receptacle and the next adjacent one, a series of vertical tubes, one mounted in each receptacle with its lower end separated from the

bottom of the receptacle, a series of air pipes each arranged to deliver air to one of the receptacles directly below the tube to agitate the mixture in the tube and force it upward therethrough, a series of shelves each arranged to receive the mixture delivered from the upper end of one of the tubes and to guide it over the common dividing wall and into the next adjacent receptacle, and a series of deflectors each arranged immediately above 70 one of the tubes to engage the mixture discharged upward from the tube and deflect it downward onto the corresponding shelf.

9. In an agitator for ore treatment, the combination of two parallel integral sheet 80 metal side walls, a bottom structure connecting the side walls, a series of sheet metal partitions connected to and extending transversely between the two side walls to form separate receptacles, means for delivering into one of the receptacles a mixture of solvent solution and finely divided ore, and means in each of the receptacles for agitating the mixture and delivering it to the next adjacent receptacle. 85

10. In an agitator for ore treatment, the combination of two parallel integral sheet metal side walls, a bottom structure connecting the side walls, a series of sheet metal partitions connected to and extending transversely between the two side walls to form separate receptacles, a series of substantially horizontal shelves extending transversely between the two side walls each connected 95 at one edge with the upper end of one of the partitions, means for delivering into one of the receptacles a mixture of solvent solution and finely divided ore, and means in each of the receptacles for agitating the mixture and delivering it onto the corresponding shelf by which it is guided to the next adjacent receptacle. 100

11. In an agitator for ore treatment, the combination of a series of adjacent receptacles, each adapted to contain a mixture of 110 solvent solution and finely divided ore, a series of vertical tubes, one mounted in each receptacle with its lower end separated from the bottom of the receptacle, a series of air pipes each arranged to deliver air to one of the receptacles directly below the tube to agitate the mixture in the tube and force it upward therethrough, means at the tops of the tubes for receiving the mixture from the tubes and guiding it into the respectively adjacent receptacles, and a plurality of valves, one at the end of each air pipe, each valve being constructed to be automatically closed and to be opened by air pressure in the pipe, and all of the valves co-operating 115 to equalize the agitating and discharging action of the air in the several receptacles. 120

12. In an agitator for ore treatment, the combination of a series of adjacent receptacles, each adapted to contain a mixture of 125

solvent solution and finely divided ore, a series of vertical tubes, one mounted in each receptacle with its lower end separated from the bottom of the receptacle, a series of air pipes each arranged to deliver air to one of the receptacles directly below the tube to agitate the mixture in the tube and force it upward therethrough, means at the tops of the tubes for receiving the mixture from the tubes and guiding it into the respectively adjacent receptacles, and devices at the ends

of the air pipes for equalizing the flow of air from them, whereby a more rapid discharge of mixture from one tube than from another is prevented.

15

In testimony whereof, I affix my signature, in presence of two witnesses.
